UNITED STATES PATENT OFFICE.

GEORGE H. STATEN, OF PORTSMOUTH, OHIO.

MATCH-SAFE.

SPECIFICATION forming part of Letters Patent No. 700,451, dated May 20, 1902.

Application filed December 10, 1901. Serial No. 85,410. (No model.)

To all whom it may concern:

Be it known that I, GEORGE H. STATEN, a citizen of the United States, residing at Portsmouth, in the county of Scioto and State of Ohio, have invented certain new and useful Improvements in Match-Safes; and I do declare the following to be a full, clear, and exact description of the invention, such as will enable others skilled in the art to which it applies to make and use the same, reference being had to the accompanying drawings, and to the figures of reference marked thereon, which form a part of this specification.

The object of this invention is to provide a match-safe which is simple in construction and adapted to receive a tray of an ordinary match-box, which tray, with its matches, can be bodily introduced into position.

A further object of the invention is to provide a match-safe which will make it impossible for the matches to be taken out in large quantities and which will therefore prevent the stealing of the matches.

Generally the construction and arrangement of the invention consists in an elongated substantially oblong-shaped plate, in the lower end of which is formed a transverse match-slot opening into a finger-aperture, through the medium of which the matches may be removed from a holder secured to the under side of the plate adjacent to the match-slot, and a stand of novel construction which supports the plate in an inclined position and has formed at its upper end portion adjacent to the plate shoulders which support the upper end of the match-box tray.

Referring to the accompanying drawings, Figure 1 is a perspective view of my invention complete. Fig. 2 is a central longitudinal section of the same, showing a match-tray inserted and indicating matches lodged in the lower end. Fig. 3 is a detail perspective of the match-box holder detached from the plate, and Fig. 4 is a detail perspective of the supporting-bracket detached.

Referring to the accompanying drawings, 1 designates a substantially oblong plate, in the lower end of which is formed a transverse match-slot 2, opening into a finger-aperture 3, through the medium of which the matches can be grasped and removed through the slot

2 from a match-tray supported in a holder 4, secured to the under side of the plate 1 adjacent to the match-slot.

The holder 4, into which the lower end of the match-tray is placed, is composed of a bottom 5, sides 6, and end piece 7, against which the end of the match-tray lodges and is held, as clearly shown in Fig. 2 of the drawings. The holder 4 is of such size and capacity to take in the lower end of the shallow match-tray in which what are commonly known as "parlor-matches" are purchased, and is secured to the plate 1 by prongs 8, formed integral with the sides 6 of the holder. By this arrangement the plate 1 forms the cover of the holder, the upper end being left open to receive the match-tray.

In order to support the upper end of the match-tray and at the same time provide means to support the match-safe in an inclined position, a bracket is employed of the following-described construction: The bracket consists of a single piece of suitable material formed with a transverse base 9, bent upwardly and inwardly, as at 10, and then outwardly in horizontal planes, as at 11, thereby forming a shoulder constituting seats on which the match-tray rests, then extending vertically, constituting side pieces to prevent lateral displacement of the tray, and formed at their upper ends with prongs 12, adapted to pierce the plate 1 and to be turned down upon the same, as indicated in Fig. 1 of the drawings. After the shallow tray has been inserted in the holder it is securely held in position by a prong or hook 13, formed integral on the upper edge of the bottom 5 of the tray-holder, as clearly shown in Figs. 2 and 3.

It will be obvious that the space above the match-slot on the plate 1 may be used for advertising purposes.

The plate 1, below the match-slot 2, is preferably roughened, as shown in the drawings, so that the matches can be readily struck thereon.

Having thus fully described my invention, what I claim as new is—

1. A match-safe comprising an elongated plate having a match-slot in its lower portion, a match-tray holder secured to the under side of the plate adjacent the said match-slot,

means formed integral with the tray-holder for preventing the withdrawal of the match-tray, and a bracket secured to the plate adjacent to its upper end for supporting the said 5 plate in an inclined position.

2. A match-safe comprising an elongated plate having a transverse match-slot opening into a finger-aperture formed in its lower portion, a tray-holder secured to the under side 10 of the plate adjacent the said match-slot to receive and retain the lower end of a match-tray, and a supporting-stand secured to the plate, having formed in its upper portion means for supporting the upper end of the 15 match-tray.

3. A match-safe comprising an elongated plate having a match-slot formed in its lower portion, a tray-holder secured to the under side of the plate adjacent the said match-slot, 20 a bracket secured to the said plate adjacent its upper end, a bracket having shoulders in alignment with the bottom of the tray-holder and adapted to support the upper end of the match-tray.

25 4. A match-safe comprising a plate having a transverse match-slot opening into a finger-aperture formed in its lower portion, a match-tray holder having prongs formed integral

therewith adapted to be inserted into the plate to secure the holder in position, and a bracket 30 for holding the safe in an inclined position.

5. A match-safe comprising a plate having a transverse slot opening into a finger-aperture formed in its lower portion, a tray-holder secured to the under side of the plate adjacent 35 the said match-slot, means to prevent the withdrawal of the match-tray and a bracket for supporting the match-safe secured to the plate adjacent its upper end and having its upper end provided with a support for the upper end 40 of the said match-tray.

6. A match-safe comprising a plate having a match-slot formed in its lower portion, a match-tray holder formed with prongs adapted to be inserted into the plate to secure the 45 holder in position, an integral prong on the upper edge of the tray-holder for preventing the withdrawal of the tray and means for holding the safe in position.

In testimony whereof I affix my signature 50 in presence of two witnesses.

GEORGE H. STATEN.
